UNITED STATES PATENT OFFICE.

ALBERT R. ABBOTT, OF BOSTON, MASSACHUSETTS.

CASH REGISTER AND RECORDER.

SPECIFICATION forming part of Letters Patent No. 474,278, dated May 3, 1892.

Application filed November 11, 1891. Serial No. 411,601. (No model.)

To all whom it may concern:

Be it known that I, ALBERT R. ABBOTT, of Boston, in the county of Suffolk and State of Massachusetts, have invented a new and Improved Cash Register and Recorder, of which the following is a full, clear, and exact description.

The object of the invention is to provide a new and improved cash register and recorder which is simple and durable in construction, very effective in operation, not requiring frequent resetting, and is arranged to add up the various sales made, at the same time showing the amount of the individual sale and delivering a check or ticket on opening the money-drawer, and also ringing a bell.

The invention consists of certain parts and details and combinations of the same, as will be fully described hereinafter, and then pointed out in the claims.

Reference is to be had to the accompanying drawings, forming a part of this specification, in which similar letters of reference indicate corresponding parts in all the figures.

Figure 1 is a transverse section of the improvement. Fig. 2 is a sectional front view of the same on the line 2 2 of Fig. 1. Fig. 3 is a sectional plan view of the same on the line 3 3 of Fig. 1, and Fig. 4 is a transverse section of the adding device on the line 4 4 of Fig. 3.

The improved cash register and recorder is provided with a suitably-constructed casing A, in which are mounted to slide transversely sets of keys B B' B², having their bearings in the front A' of the casing and in a transverse bar A², as is plainly shown in Fig. 3. The sets of keys are preferably arranged in tiers, located one above the other, each key being provided at its outer end with a finger-piece marked with a numeral, the sets of keys B being for even numbers, representing cents, the keys B' for odd numbers, also representing cents, and the keys B² with numbers for representing dollars. Each key is provided on the inside of the casing A with a pin B³, engaging one arm C' of a bell-crank lever C, fulcrumed on a transversely-extending rod C², secured in the sides of the casing A. The other arm C³ of each bell-crank lever C is pivotally connected with an upwardly-extending rod D, formed at its upper end into a plate D',

carrying a numeral on both sides corresponding to the numeral of the respective key with which its bell-crank lever is connected. The 55 plates D' when moved to an uppermost position are visible from the outside of the casing through panes of glass A³ and A⁴, arranged transversely in an offset A⁵, secured on top of the casing A. The panes of glass A³ and A⁴ 60 are located opposite each other in opposite sides of the plate D', so that an operator manipulating the keys B B' B² can see the numeral displayed on the respective keyboard and the purchaser can also see the amount of 65 his purchase registered through the pane of glass A⁴. Each rod D is also provided with a wedge D², located below the plate D' and adapted to pass between transversely-extending bars D³ and D⁴, of which the bar D³ is 70 mounted to slide horizontally in suitable bearings A⁶, formed on the inside of the sides of the casing A. The other bar D⁴ is fixed in the sides of the casing, and when the rod D is moved upward its wedge D² presses the 75 movable part D³ outward against the tension of springs D⁵, held in the bearings A⁶. When the base of the wedge D² has passed the bar D³, then the latter closes under the base of the wedge D², thus locking the rod D in an 80 uppermost position, with its plate D' in the offset A⁵ to permit its numeral to be seen from both sides.

In order to open the bar D³ to permit the rod D to drop into a normal position, wedges 85 D⁶ are employed adapted to pass between the movable bar D³ and the fixed bar D⁴ from above and at their ends, the said wedges D⁶ being held on rods D⁷, extending vertically and pivotally connected at their lower ends 90 with arms E, secured on a shaft E', mounted to turn in suitable bearings in the sides of the casing A. The shaft E' carries arms E², extending upward and connected with each other by a transversely-extending rod E³, 95 adapted to be engaged by the inner ends of the keys B B' B².

In order to hold the arms E and E², as well as the shaft E' in a normal position, a spring E⁴ is employed, pressing on the arms E², so as 100 to hold the rod E³ in contact with the inner ends of the keys B B' B². When one of the keys is pressed, the rod E³ is caused to swing inward, so that the arms E² move likewise

and turn the shaft E', which swings the arms E downward, thus drawing the rods D⁷ in a like direction and engaging the wedges D⁶ with the movable bar D³ and the fixed bar D⁴, 5 so as to press the movable bar D³ outward to permit the rod D, which was in an uppermost position, to drop downward. Suitable weights C⁴ may be held on the arms C³ of the bell-crank lever C, so as to insure a return movement 10 of the respective bell-crank lever and the key connected with it.

On one of the arms E is pivoted a spring-pressed pawl E⁶, adapted to engage an arm E⁷, secured on the shaft carrying the striker E⁸, 15 adapted to sound a bell E⁹, supported in the casing. Thus when a key is pressed inward the arm E, carrying the pawl E⁶, acts on the arm E⁷ so that the striker E⁸ is moved outward away from the bell E⁹, and when the 20 pawl E⁶ has passed the arm E⁷ the striker simply returns, by the action of a spring or other means, and sounds the bell E⁹. The arm E is also pivotally connected by a link F with a latch F', pivoted at F² in the casing A and 25 formed on its top with a notch F³, adapted to engage a fixed bar F⁴, held on the rear end of the money-drawer F⁵, mounted to slide in the bottom of the casing A and adapted to be drawn open by the action of a coiled spring 30 F⁶, attached by one end to the rear end of the said drawer and by its other end to the front of the casing A. The free end of the latch F' is beveled, as is plainly shown in Fig. 1, so that when the drawer F⁵ is pushed shut against 35 the tension of the spring F⁶ then the fixed rod F⁴ travels up the bevel and finally engages the notch F³, so that the latch F' locks the drawer F⁵ in position.

On the under side of each key, within the 40 casing A, is pivoted a spring-pressed pawl G, engaging a ratchet-wheel G', mounted to turn loosely on a transversely-extending rod G², held in the sides of the casing A. Each ratchet-wheel G' carries on one face a wheel G³, be- 45 low which is located a smaller wheel G⁴, between which and the wheel G³ passes a strip of paper G⁵, unwinding from a roll of paper G⁶, mounted to turn in the rear part of the casing, as is plainly shown in Fig. 1. The 50 strip of paper G⁵ after leaving the wheels G³ and G⁴ extends upward and over a type-wheel H, secured on a shaft H', mounted to turn in suitable bearings in the sides of the casing A, one end of the said shaft extending to the 55 outside of the casing and carrying on its outer end a knob or handle H² for turning the shaft. On the knob or handle is also secured a pointer H³, indicating on a dial H⁴ attached to the outside of one of the sides of the casing. 60 A and containing characters corresponding to the characters on the type-wheel, so that the position of the type is indicated by the pointer H³ on the corresponding character of the dial H⁴. 65 Each type-wheel H is made of two wheels H⁵ and H⁶, of which the wheel H⁶ is mounted to turn loosely on the wheel H⁵ and is provided

between each two successive characters with a slot H⁷, adapted to be engaged by a lug H⁸, projecting from a rod H⁹, mounted to slide 70 transversely in the sides of the casing A and under the control of the operator. When the lugs H⁸ engage the notches in the wheels H⁵, the latter are locked in place, and when the shaft H' is turned only the wheels H⁵ turn. 75 When the bar H⁹ is shifted transversely by the operator to one side and when the money-drawer F⁵ is opened to permit the operator to take hold of the said bar, then the lugs H⁸ are disengaged from the notches H⁷ and the wheels H⁶ are free to turn with the wheel H⁵ when the shaft H' is rotated. The wheel H⁵ is formed on its rim with numerals "1" to "31" for indicating the day of the month, and the wheel H⁶ is formed at its rim between the notches 85 with the name of the month, the twelve months of the year being indicated on the entire rim of the wheel. The paper passes under a protecting-plate I, located above the wheels H⁵ and also passes over a transversely-ar- 90 ranged fixed bar I', located on one side of the wheel and having its front surface extending vertically and tangentially to the rim of the wheel. On this fixed bar I' are characters indicating "amount of sale." Opposite this 95 bar I' and the characters on the wheels H⁵ and H⁶, directly above the said bar, is ar- ranged a platen B⁴—one for each key B B' B²—and the corresponding type-wheel H. Thus 100 when a key is pressed inward the platen B⁴ moves against the paper extending on the right-hand side of the wheels and over the bar I', so that the paper is pressed upon the characters on the wheels H⁵ and H⁶ of the re- 105 spective type-wheel and upon the type-bar I', so that the characters on the latter, as well as the type on the respective type-wheel, are printed on the paper.

Directly over the platen B⁴ of each lever is arranged a knife B⁵, adapted to cut the paper 110 directly above the characters on the wheels H⁵ H⁶, from which characters the impression had been made, the knife B⁵ passing upon the paper and cutting the same on the rims of the wheels. The ticket or coupon thus cut 115 off the strip of paper G⁵ drops downward into the money-drawer F⁵, then in an open position. The inward movement of each key feeds the strip of paper G⁵ forward over the 120 respective type-wheel H by the action of the pawl G turning the ratchet-wheel G', and con-sequently the wheel G³. The paper passing between the latter and the wheel G⁴ is thus pushed forward over the type-wheel, the 125 amount of forward feed corresponding to the space occupied by the front face of the type- 130 bar I' and one set of characters on the two wheels H⁵ and H⁶.

In order to record and add up the sales in a stated time, the following device is pro- 130 vided, being actuated from the keys B, B', and B². The device is provided with a suitably-constructed casing J, arranged on one side of the casing A and provided with a ver-

tical bar J' , mounted to slide in suitable bearings in one side of the casing A. On the inner face of this sliding bar J' are arranged the pins J^2 and J^3 , located one above the other, 5 and similar pins J^2 J^3 are arranged in a bar J^4 , mounted to slide vertically in the other side of the casing A and directly opposite the sliding bar J' . Springs J^5 press on the lower ends of the sliding bars J' and J^4 , so as to 10 hold the same in a normal position. The pins J^2 J^3 in the two sliding bars J' and J^4 are adapted to be engaged by the beveled ends of the pawls K and K' , respectively, pivoted on the levers K^2 and K^3 , respectively, fulcrumed 15 at K^4 and K^5 on the sides of the casing A. The pawls K and K' are spring-pressed, so as to engage with their beveled ends the respective pins J^2 and J^3 , the pawls being prevented from slipping upward by fixed bars 20 J^6 , attached to the inside of the casing A, across the bars J' and J^4 . The levers K^2 on the opposite sides of the casing A are connected with each other at their lower ends by a transverse bar K^6 , adapted to be engaged 25 by projections or lugs B^6 on the keys B and B^2 , so that when one of the latter is pressed this projection presses on the bar K^6 , thus imparting a swinging motion to the levers K^2 , which by their pawls K press on the pins J^2 , 30 thus imparting a downward sliding motion to the bars J' and J^4 ; consequently to the casing J and its contents. The levers K^3 are similarly connected with each other by a bar K^7 , which is actuated by the projections or 35 lugs B^7 on the keys B' , so that when one of the latter is pressed inward the levers K^3 are caused to swing, and the pawls K' , acting on the pins J^3 , press the bars J' J^4 downward, thus moving the casing J in a like direction. 40 In the two bars J' and J^4 are mounted to turn the gear-wheels L and L' , extending throughout the width of the casing A, as is plainly shown in Fig. 2. The gear-wheels L and L' are adapted to be engaged by segmental gear-wheels L^2 and L^3 , respectively, 45 secured on shafts L^4 and L^5 , respectively, mounted to turn in suitable bearings in the sides of the casing A. The segmental gear-wheels L^2 are pivotally connected with the set 50 of keys B^2 , and the other segmental gear-wheels L^3 are pivotally connected with the keys B' and B, as is plainly shown in Fig. 1. Thus when a key B is pressed the levers K^2 and pawls K cause a downward swinging motion 55 of the bars J' and J^4 , so that the gear-wheels L and L' move downward such a distance that the gear-wheel L' is engaged by the segmental gear-wheel L^3 , connected with the pressed key B, the said key imparting a swing- 60 ing motion to the said respective segmental gear-wheel L^3 , so as to turn the gear-wheel L' . In a like manner, when one of the other keys B' is pressed, the levers K^3 are caused to swing, and by their pawls K' engaging the pins J^3 65 cause a downward swinging motion of the bars J' and J^4 , so that the gear-wheels L and L' are moved into a lowermost position, the

gear-wheel L' being engaged by that segmental gear-wheel L^3 receiving a swinging motion from the pressed key of the set of keys B' . When the pressure on the pressed key ceases, the parts are returned to their proper positions by springs connected with the levers K^2 and K^3 , as is plainly shown in Fig. 1. The pawls K and K' are thus moved outward away 70 from the pins J^2 and J^3 , so that the bars J' and J^4 return to their normal position by the action of the springs J^5 . One of the levers K^3 is also pivotally connected by a link N with a slide mounted to slide horizontally in suitable guideways N^2 , attached to the inside of one of the sides of the casing A. The slide N' is provided on its under side with rack-teeth N^3 , adapted to mesh in a gear-wheel N^5 , attached to a shaft N^4 , mounted to turn in suitable bearings in the bar J' below the gear-wheel L' , previously mentioned. When the lever K^3 receives an inward swinging motion by pressing upon one of the keys of the sets of keys B' , then the link N pushes the slide 80 N' rearward, so that the rack-teeth N^3 move to the left above the gear-wheel N^5 , which latter is then in a lowermost position, and is consequently not acted on by the rack-teeth N^3 . When the lever K^3 returns to its normal 85 position and the bars J' and J^4 slide upward, then the slide N' is on its return movement, and by its rack-teeth N^3 engages the gear-wheel N^5 , thus rotating the same and its shaft N^4 . 90 Each of the pawls K and K' is provided with a recess K^8 and a bevel K^9 , extending forward from the recess, as is plainly shown in dotted lines in Fig. 1, so that when the levers K^2 and K^3 have moved into their innermost positions the pins J^2 and J^3 engage the said recesses 95 K^8 and the return movement of the bars J' and J^4 takes place, this return movement being suddenly caused by the action of the springs J^5 . When a key B^2 is pressed, its lug B^6 acts on the bar K^6 of the levers K^2 , so that 100 the pawls K of the latter press the bars J' and J^4 downward to move the gear-wheel L into the path of the segmental gear-wheel L^2 , which latter then receives a swinging motion by the pressed key B^2 . The shaft of the gear-wheel L operates the mechanism for adding 105 dollars, while the shaft of the gear-wheel L' serves to add the tens both of even and uneven numbers from the keys B and B' . In addition, the gear-wheel N^5 , actuated by the key B' , carrying uneven numbers, adds the unit "5" whenever a key B' is actuated, it 110 being understood that the keys B and B' only move tens, and in order to make up for the fraction of a unit "5" the keys B' actuate the units gear-wheel N^5 . One of the keys B is not 115 connected with the segmental gear-wheel L^3 , and only acts on the bar K^7 of the levers K^3 , so that the slide N' only is actuated, and when the lever K^3 returns the rack-teeth N^3 actuate the units gear-wheel N^5 , so that an addition of only five cents is made. 120 125 130 The two keys B and B' , carrying the numerals "10" and "15," respectively, are con-

nnected with segmental gear-wheels L^3 , having a like number of teeth, so that when either of the said two keys is pressed the gear-wheel L' is turned the same distance; but, in addition, 5 when the key B' is pressed, the units gear-wheel N^5 is turned, so that the sum of "10" and "15" is added in the adding-machine. When the key B of the numeral "10" is pressed, the gear-wheel L' is turned the same distance 10 as when the key B' , having numeral "15," is actuated, so that, as far as the gear-wheel L' is concerned the latter is turned the same distance on pressing either of the keys B and B' , bearing the numerals "10" and "15," respectively. The pressing of the key B with numeral "10," however, does not actuate the units gear-wheel N^5 , so that only ten cents is added, while when the key B' , carrying the numeral "15," is pressed, ten is added by the 15 gear-wheel L' and five by the units-wheel N^5 . A like arrangement is made on the other keys—that is, the key B , carrying, for instance, the numeral "30," when pressed turns the gear-wheel L' the same distance as when the key B' , carrying the numeral "35," is pressed; but the latter key also actuates the units gear-wheel N^5 , so that an addition is actually made 20 in the adding-machine when the key B' , having numeral "35," is pressed.

30 It is understood that the number of teeth of the several sets of segmental gear-wheels L^3 increases according as the value of the numerals increases, so that the gear-wheel L' is turned a corresponding distance to properly 35 add up the amount indicated by the key pressed. The upper set of keys B^2 actuates the levers K^2 for shifting the bars J' and J^4 into a lowermost position for the respective segmental gear-wheel L^2 to turn the gear-wheel 40 L . The segmental gear-wheels L^2 for the several keys B^2 have such a relative number of teeth as to add the proper amount in dollars.

The shaft N^4 , carrying the units gear-wheel N^5 , extends into the inside of the casing J and carries thereon a gear-wheel N^6 , in mesh with a gear-wheel N^7 , secured on a transversely-extending shaft O , mounted to turn in 45 suitable bearings in the casing J . On the shaft O is secured a sprocket-wheel O' , connected by a sprocket-chain O^2 with a sprocket-wheel O^3 , formed on the hub of the units-wheel O^4 , provided on its rim with the successive numerals "0" to "9," adapted to appear 50 in an opening J^7 in the front of the casing J . The units-wheel O^4 is mounted to turn on the hub P of the tens-wheel P' , also provided with the numerals "0" to "9" in succession and arranged alongside the units-wheel O^4 . The two wheels P' and O^4 when read together indicate cents. The tens-wheel P' is mounted to turn on the hub Q of the units dollar-wheel Q' , having numerals "0" to "9" in succession on its rim, the said units dollar-wheel being arranged next to the tens cent-wheel P' . 55 The units dollar-wheel Q' is mounted to turn loosely on a shaft R , extending transversely

and carrying the tens dollar-wheel R' , arranged next to the units dollar-wheel Q' .

On the hub P of the tens cent-wheel P' is formed or secured a sprocket-wheel P^2 , over which passes a sprocket-chain P^3 , also passing over a sprocket-wheel P^4 , secured on the shaft L^6 of the gear-wheel L' , previously mentioned. Thus, when the latter is rotated, its motion is transmitted by the sprocket-wheel P^4 , the sprocket-chain P^3 , and the sprocket-wheel P^2 to the tens cent-wheel P' , to properly indicate the amount of the respective key pressed. In case a key B' is pressed with an odd numeral the shaft L^6 , as well as the shaft O , is actuated in the manner previously described, so that the tens and the units are added on the wheels P' and O^4 .

On the shaft L^6 is secured a star-wheel P^5 , having ten teeth adapted to be engaged by a pin O^6 on a wheel O^5 , attached on the shaft O . Thus one complete revolution of the wheel O^5 moves the wheel P^5 the distance of one tooth, thus actuating the shaft L^6 and the tens-wheel P' to indicate the proper amount. 85 The hub Q of the units dollar-wheel Q' carries a sprocket-wheel Q^2 , over which passes a sprocket-chain Q^3 , also passing over a sprocket-wheel Q^4 , secured on a shaft Q^5 , extending transversely and mounted to turn in suitable 90 bearings in the casing J . The shaft Q^5 carries a bevel gear-wheel Q^6 in mesh with a bevel gear-wheel Q^7 , secured on a shaft Q^8 , extending angularly at one side of the casing J , and carrying at its upper end a bevel gear-wheel L^7 in mesh with a bevel gear-wheel L^8 , attached to the shaft L^9 of the upper gear-wheel L , previously mentioned. Thus when the latter is actuated by pressing one of the said keys B^2 the motion of the said gear-wheel L is transmitted by the bevel gear-wheel L^8 to the bevel gear-wheel L^7 and to the shaft of the latter Q^8 . The motion of the shaft Q^8 is transmitted by the gear-wheels Q^7 100 Q^6 to the shaft Q^5 , which, by the sprocket-wheel Q^4 , the chain Q^3 , and the sprocket-wheel Q^2 , imparts a rotary motion to the units dollar-wheel Q' .

On the shaft Q^5 is secured a star-wheel S , adapted to be turned by a pin P^6 on the wheel P^5 , previously mentioned, it being understood that every revolution of the wheel P^5 moves the star-wheel S the distance between two teeth. Thus when the shaft L^6 makes one complete revolution the shaft O^5 115 is rotated, so that the wheel Q' makes one-tenth of a revolution, and the next following numeral is brought into the opening J^7 , thus registering the one hundred cents or one dollar from the wheels P' and O^4 .

On the star-wheel S is secured a pin S' , adapted to engage a star-wheel S^2 , secured on a shaft S^3 , mounted to turn in suitable bearings in the casing J , the shaft S^3 , carrying a sprocket-wheel S^4 , connected by a sprocket-chain S^5 with a sprocket-wheel S^6 , secured on the shaft R , carrying the tens dollar-wheel 125

R', previously mentioned. Each complete revolution of the wheel S moves the star-wheel S² around one-tenth part, so that the shaft S³ is rotated and its motion is transmitted to the tens dollar-wheel R', which latter thus registers the proper amount.

The star-wheel S² is provided with a pin S', adapted to engage a star-wheel T, also having ten teeth and secured on a shaft T', mounted to turn in suitable bearings in the casing J, the said shaft carrying a sprocket-wheel T², over which passes a sprocket-chain T³, also passing over the sprocket-wheel T⁴, secured on the hub T⁵ of the hundreds dollar-wheel T⁶, provided with successive numerals up to "10" on its rim and located next to the tens dollar-wheel R'. The hundreds dollar-wheel T⁶ is mounted to turn loosely on the shaft R, as is plainly shown in Fig. 2. When the wheel S² has made one complete revolution, its pin S' moves the star-wheel T the distance between two teeth, thus turning the shaft T'. The movement of the latter is transmitted by the sprocket-wheels T² and T⁴ and the sprocket-chain T³ to the hundreds dollar-wheel T⁶, which is thus turned to bring the next following numeral into the opening J⁷.

On the face of the star-wheel T is secured a pin T⁷, adapted to engage at every revolution a star-wheel U, having ten teeth and being secured on a shaft U', also mounted to turn in the casing J. On the shaft U' is secured a sprocket-wheel U², over which passes a sprocket-chain U³, also passing over a sprocket-wheel U⁴, formed on a hub of the thousands dollar-wheel U⁵, mounted to turn loosely on the hub T⁵ of the hundreds dollar-wheel T⁶. The thousands dollar-wheel U⁵ is arranged alongside the hundreds dollar-wheel T⁶, and its numerals also appear in the opening J⁷. When the wheel T makes one revolution, its pin T⁷ moves the star-wheel U the distance between two teeth, the movement being transmitted to the shaft U' and from the latter by the sprocket-wheels U² and U⁴ and sprocket-chain U³ to the thousands wheel U⁵, so that the latter brings the next following numeral into the opening J⁷. Thus it will be seen that when the key B', marked with numeral "5," is pressed, the lever K³ by the rack-teeth N³ actuates the wheel N⁵, and the latter by its connection with the units cent-wheel O⁴ moves the latter to bring the next following numeral into the opening J⁷. When a key B is pressed, the lever K² is actuated to move the slide J' into proper position and also to actuate the corresponding segmental gear-wheel L³ to turn the gear-wheel L' the proper distance. The movement of the gear-wheel L' is transmitted by the shaft L⁶ and the sprocket-wheel P⁴, chain P³, and sprocket-wheel P' to the tens cent-wheel P' in the manner above described, so that the proper numeral corresponding to the numeral of the key pressed appears in the opening J⁷. The amount of the units-wheel O⁴ stands beside it,

and consequently the total amount appears in the opening J⁷. When a key B' is pressed, then the shafts L⁶ and O are actuated—that is, the shaft L⁶ is actuated on the inward movement of the key B' and the shaft O on the return movement of the same. Thus the proper amount on the tens cent-wheel P' is registered and the units added on the wheel O⁴. When the amount is more than one dollar, the dollar-wheel Q' is actuated from the shaft L⁶ in the manner previously described. When a dollar-key B² is pressed, the gear-wheel L is actuated and its motion is transmitted to the shaft Q⁵ and from the latter to the dollar-wheel Q', as above described, so that the proper sum is added on the said wheel and the total amount appears in the opening J⁷. The tens dollar-wheel R' is actuated from the shaft Q⁵ in the manner above described, and in a like manner the hundreds and thousands dollar-wheels to register the proper total amount. Suitable springs may be employed in the casing J to hold the indicating-wheels O⁴, P', Q', R', T⁶, and U⁵ in position to prevent their accidental turning. It will further be seen that whenever the keys B, B', and B² are in their normal outermost position the adding device is completely disconnected from the said keys as the gear-wheels L, L', and N⁵ are disengaged from the segmental racks L² and L³ and the rack-teeth N³, respectively. The casing J, with the adding mechanism, is moved down in position whenever a key is pressed and is actuated during the time the key is pressed and returned in case a unit is to be added. The casing J moves back to its normal uppermost position when the respective key is returning.

It is understood that this machine when actuating the keys B, B', and B² indicates each individual sale, and also shows the total amount of the previous sales. The device also displays a tablet showing the amount of the sale, at the same time dropping the previously-displayed tablet. It prints the amount of a sale on a strip of paper and cuts the paper to drop a coupon or ticket with the amount of the sale, date, &c. When a key is pressed, the money-drawer is opened and a bell is also sounded.

Having thus described my invention, I claim as new and desire to secure by Letters Patent—

1. In a machine of the class described, the combination, with two sets of keys, of which one is for odd and the other for even numerals, of levers adapted to be actuated from the said keys, pawls held on the said levers, sliding bars provided with pins actuated from the said pawls, gear-wheels mounted to turn in the said sliding bars, and segmental gear-wheels connected with the said keys and adapted to engage the said gear-wheels, substantially as shown and described.

2. In a machine of the class described, the combination, with an adding-machine provided with a casing having connected bars

- mounted to slide vertically, of driving gear-wheels journaled in the said bars and adapted to actuate the said adding-machine, segmental gear-wheels adapted to be engaged by 5 the said driving gear-wheels at the downward movement of the said casing, and two sets of keys, of which one is for odd and the other for even numerals, the said keys serving to actuate the said segmental gear-wheels, substantially as shown and described.
3. In a machine of the class described, the combination, with an adding-machine provided with a casing having connected bars mounted to slide vertically, of driving gear-wheels journaled in the said bars and adapted to actuate the said adding-machine, segmental gear-wheels adapted to be engaged by 15 the said driving gear-wheels at the downward movement of the said casing, two sets of keys, of which one is for odd and the other for even numerals, the said keys serving to actuate the said segmental gear-wheels, and means, substantially as described, for moving the said bars, the driving gear-wheels, and casing 20 in a lowermost position, so that the driving gear-wheels engage the segmental gear-wheels, as set forth.
4. In a machine of the class described, the combination, with sliding bars supporting the 25 adding-machine and provided with pins and gear-wheels for actuating the adding-machine, of pawls for pressing on the said pins to impart a sliding motion to the said bars, levers carrying the said pawls, and keys for actuating the said levers, substantially as shown and described.
5. In a machine of the class described, the combination, with sliding bars supporting the adding-machine and provided with pins and 30 gear-wheels for actuating the adding-machine, of pawls for pressing on the said pins to impart a sliding motion to the said bars, levers carrying the said pawls, keys for actuating the said levers, and segmental gear-wheels 35 pivotally connected with the said levers and adapted to engage the said driving gear-wheels of the adding-machine, substantially as shown and described.
6. In a machine of the class described, the combination, with an adding-machine provided with a gear-wheel for actuating the tens mechanism and a gear-wheel for actuating the units mechanism, of a set of keys for actuating the said gear-wheels in succession, levers 40 connected by a bar adapted to be engaged by the said keys, a rack-slide connected with the said levers and adapted to engage the gear-wheel of the units mechanism, and a

segmental gear-wheel pivotally connected with the set of keys and adapted to actuate the gear-wheel for the tens mechanism, substantially as shown and described.

7. In a machine of the class described, the combination, with an adding-machine provided with a gear-wheel for actuating the tens mechanism and a gear wheel for actuating the units mechanism, of a set of keys for actuating the said gear-wheels in succession, levers connected by a bar adapted to be engaged by the said keys, a rack-slide connected with the said levers and adapted to engage the gear-wheel of the units mechanism, a segmental gear-wheel pivotally connected with the set of keys and adapted to actuate the gear-wheel for the tens mechanism, and a link connecting the said levers with the said slide, so as to actuate the units gear-wheel on the return motion of the pressed key, substantially as shown and described.

8. In a machine of the class described, the combination, with a series of keys, of segmental gear-wheels pivotally connected with the said keys and an adding-machine having a casing mounted to slide vertically and provided with driving gear-wheels adapted to engage the said segmental gear-wheels, substantially as shown and described.

9. In a machine of the class described, the combination, with a series of keys, of segmental gear-wheels pivotally connected with the said keys, an adding-machine having a casing mounted to slide vertically and provided with driving gear-wheels adapted to engage the said segmental gear-wheels, and intermediate mechanism, substantially as described, for connecting the said keys with the said segmental gear-wheels, as set forth.

10. In a machine of the class described, the combination, with a series of keys, of segmental gear-wheels pivotally connected with the said keys and adapted to engage a driving gear-wheel of the adding mechanism, levers connected with each other by a bar adapted to be actuated by the said keys, pawls carried by the said levers, and an adding mechanism provided with a casing having sliding bars and pins secured thereon, the said pins being engaged by the said pawls to move the driving gear-wheels in position for engagement with the said segmental gear-wheels, substantially as shown and described.

ALBERT R. ABBOTT.
